ENGINE COOLING MEANS AND METHOD

Edwin L. Cline, Pasadena, Calif., assignor to
 Clayton Manufacturing Company, El Monte,
 Calif., a corporation of California

Original application May 20, 1942, Serial No.
 443,833, now Patent No. 2,452,550, dated No-
 vember 2, 1948. Divided and this application
 September 24, 1947, Serial No. 775,766

19 Claims. (Cl. 123—174)

1

The present invention relates to a cooling apparatus and method and more particularly to an auxiliary cooling apparatus and method for cooling the engine or radiator liquid of a motor vehicle while undergoing test, for example, upon a chassis dynamometer of the character disclosed in my parent copending application Serial No. 443,833, filed May 20, 1942, now Patent No. 2,452,550, November 2, 1948, and of which the instant application is a division.

An important feature of the invention is the provision of a cooling system of the "closed" type having a small volumetric capacity wherein the liquid for cooling the engine jacket and/or radiator is withdrawn and circulated through a heat exchanger for cooling and then returned to the engine and/or radiator at the same rate at which the liquid was withdrawn therefrom so that the supply of cooling liquid is not unduly reduced. The auxiliary cooling system may comprise a suitable length of pipe bent into the form of a spiral coil, the pipe containing a plurality of small tubes through which the cooling liquid is adapted to be circulated. The coiled heat exchanger is adapted to be connected with an engine radiator by two sections of hose, an inlet section and a return section, each having an end thereof adapted to be inserted into the upper tank portion of the radiator. These sections of hose have their other ends suitably connected with the heat exchanger and a circulating pump so that liquid is withdrawn from the radiator tank and circulated through the small tubes in the heat exchanger and then returned to said radiator tank. The circulating pump is preferably self-priming and will return all radiator liquid in the heat exchanger to the radiator through the return hose upon withdrawal of the inlet hose from said radiator.

One of the novel features of the coiled heat exchanger is that its volumetric capacity is very small and preferably does not exceed the capacity of the tank in the upper portion of the radiator of the smallest of the popular-priced cars. This makes it possible to utilize the heat exchanger to supplement the cooling effect of the motor fan and conventional radiator, utilizing at the same time whatever liquid medium is present in the radiator and engine of the car being tested. Thus, there is no possibility of loss, dilution or contamination of the liquid medium contained in the vehicle engine cooling system. This is important not only from the standpoint that it avoids the mess usually incident to opening the radiator drain valve and continuously adding cold

water to the radiator to keep the engine cool, as in conventional practice, but also is valuable from the standpoint that there is no loss when high-priced antifreeze cooling mediums are used in the engine, or when the radiator liquid contains a rust inhibitor.

The coiled heat exchanger is spirally wound, assuming the general shape of a pancake so that it is compact enough to be conveniently mounted in an instrument stand which may be provided with an instrument panel carrying direct reading meters for the speed and horsepower, respectively, developed by the car being tested. The heat exchanger is preferably cooled by water under pressure drawn from a service pipe and circulated through the heat exchanger. However, any conventional cooling means such as a fan, blower, etc., not shown, may obviously be used with the heat exchanger in lieu of water. Suitable hose sections and couplings are associated with the heat exchanger in the instrument stand for supplying the cooling water to said heat exchanger. This cooling water is preferably circulated in a direction opposite to the flow of the liquid to be cooled.

Another feature of the invention is the automatic control of the temperature of the engine made possible by a novel thermostat provided with a built-in permanent magnet enabling said thermostat to adhere to any part of the engine being tested, preferably the cylinder head itself, rather than the engine block. This thermostat is fully disclosed, and claimed, in Patent No. 2,417,860, which is a division of my parent application Serial No. 443,833, supra. The thermostat includes a Bourdon tube containing acetone or some other suitable liquid which will expand in response to temperature variations. The movable end of the Bourdon tube carries an electrical contact adapted to complete a circuit through a relay to a solenoid controlled valve in a by-pass connected with the discharge line of the coiled heat exchanger. The thermostat is arranged so that as the engine heats up, the solenoid valve will be opened, allowing a supplemental volume of cooling water to pass through the heat exchanger. When the engine has been cooled to the temperature desired, then the Bourdon tube contracts, breaking the circuit to the solenoid valve and effecting closing of said valve.

The principal object of the invention is to provide a cooling means and method for use with a dynamometer for testing the engines of motor vehicles wherein it is unnecessary to drain the car radiator of antifreeze solutions or rust

2

inhibitors with their consequent loss, contamination or dilution.

Another object of the invention is to provide an automatically controlled cooling means for cooling an engine undergoing test so that engine temperatures comparable to those experienced on the highways are reproduced for various speeds and under various conditions of load and acceleration.

Another object of the invention is to provide auxiliary engine cooling means to supplement the cooling action of a conventional radiator, including means for conveniently filling the radiator before starting a test in the event that the radiator water level is low.

A further object of the invention is to provide an auxiliary "closed" cooling system for use in testing engines including a heat exchanger which is normally initially empty, and whose capacity is less than that of the upper tank of the smallest radiator of the popular low-priced automobiles, whereby the liquid circulating through the engine and radiator can be cooled by the heat exchanger and returned to said radiator without removing any substantial volume of liquid from the engine cooling system which might otherwise cause overheating.

Further features and objects of the invention will be apparent from the following description taken in conjunction with the accompanying drawings, in which:

Fig. 1 is a perspective view of a complete portable chassis dynamometer including a dynamometer unit and an instrument stand containing the auxiliary engine cooling system comprising the present invention;

Fig. 2 diagrammatically illustrates a vehicle positioned on the chassis dynamometer unit of Fig. 1 ready to be tested;

Fig. 3 is an enlarged view of the rear of the instrument stand with portions of the casing broken away to illustrate the heat exchanger and circulating apparatus for the water of the radiator;

Fig. 4 is a sectional view through the instrument stand taken on the line 4-4 of Fig. 3;

Fig. 5 is an elevational view of the upper left side of the instrument stand;

Fig. 6 is a detailed sectional view taken on the line 6-6 of Fig. 3;

Fig. 7 is a diagrammatic view illustrating the engine radiator, and the heat exchanger and pump for cooling and circulating the radiator water and also schematically showing the circuit for the pump motor and the thermostat control for the cooling motor; and

Figs. 8 and 9 are sectional views taken on the lines 8-8 and 9-9, respectively, of Fig. 7.

Figs. 1 and 2 of the drawings illustrate a portable type of chassis dynamometer with which the auxiliary cooling means comprising the present invention may be used. However, it will be understood that the auxiliary cooling means disclosed herein is not limited to use with any particular type of dynamometer.

Briefly, the chassis dynamometer comprises a frame 1 including longitudinally extending side members 2 and 3 spaced apart and interconnected by a plurality of transverse members, only two of which, namely 4 and 5, are shown in Fig. 1. The dynamometer frame is disclosed in greater detail, and claimed, in my copending application Serial No. 775,768, filed of even date herewith, which is a continuation-in-part of my parent application, Serial No. 443,833, supra. A pair of

dynamometer rolls 10 and 11 is mounted horizontally within the frame 1 between adjacent transverse members, and these rolls are of a length sufficient to be engaged by both rear wheels of a motor vehicle while undergoing test. The roll 10 is an idler and the roll 11 is a drive roll serving as a means for transmitting the power from the rear wheels of a motor vehicle to a power absorption brake unit (not shown) contained within a housing 206.

A pair of ramp members 23 is provided to enable a vehicle to be backed onto the rolls 10 and 11 for test purposes. The ramps are maintained in operative relation to the side member 3 by means of removable screws 26 which enable the ramps to be readily detached when desired. An additional pair of ramps 23a (Fig. 2) may be secured to the side member 2 in order to enable a vehicle to be driven forwardly onto the rolls 10 and 11. When in use, the dynamometer frame 1 is supported in spaced relation to a floor by four rubber padded feet 38 arranged adjacent the opposite ends of the rolls 10 and 11 and a pair of metal stabilizing feet 39 arranged at the end of the frame remote from said rolls. The dynamometer frame 1 is also provided with four retractable and removable casters 41 adapted to elevate the dynamometer frame 1 and to raise the feet 38-39 from the floor, whereby to enable the same to be easily moved from one location to another. The details of construction of the supporting feet and retractable casters are fully described, and claimed, in my copending application Serial No. 775,767, filed of even date herewith, and which constitutes a division of my parent application, supra.

An instrument stand S, containing the auxiliary heat exchanger, is shown in perspective in Fig. 1 and in more or less detail in Figs. 3 to 6. The instrument stand S comprises a cabinet 212 having left and right side walls 213 and 214, respectively, and front and rear main panels 215 and 216, respectively. The cabinet is streamlined and has a cross-sectional shape generally similar to that of an airplane wing, as will be evident from Figs. 1 and 4. The cabinet 212 is mounted upon legs 217 and 218 secured to the cabinet side walls 213 and 214, respectively. Each of the legs 217 and 218 carries a flange 219 at its upper end which is secured to the end walls of the cabinet by screws 220. The lower portion of each of the legs 217 and 218 includes a triangular section generally designated by the numeral 221. The sides of the triangular portion extend beyond the base of said triangular portion and are provided with casters 222 enabling the instrument stand S to be readily moved from one location to another. The legs 217 and 218 are further connected to the stand S by an inwardly extending section 223 carrying a flange 224 similar to the flange 219, said flange being secured to the side walls of the stand by suitable screws 225.

The auxiliary cooling equipment contained within the instrument stand S comprises a motor 230 which is mounted upon a horizontal platform 231 by means of bolts 232. The opposite ends of the platform 231 are supported by strips of angle iron 233 suitably carried by one of the side walls 213 and an intermediate partition wall 213a, respectively, the strips of angle iron being fastened to the platform 231 by bolts 234. The platform 231 also carries a positive displacement pump 235 which is secured thereto by bolts 235a (Fig. 7) and is adapted to circulate the engine cooling water through the auxiliary cooling sys-

tem or heat exchanger, as will be explained more fully hereinafter. The shaft 236 of the motor is connected to a shaft 237 of the pump by a coupling 238. The pump shaft 237 is packed against leakage by a suitable gland 239. The radiator of the car undergoing test is diagrammatically indicated at R in Fig. 7 and contains the usual tank or space R' in the upper portion thereof above the core R². The inlet 240 of the pump 235 is connected by a section of hose 241 to an elbow 242 (Fig. 3) secured to the intermediate vertical wall 213^a within the cabinet 212. The elbow 242 has a hose section 244 connected thereto and its opposite end is adapted to be inserted through the neck of the radiator R into the space R', whereby to serve as an inlet conduit for establishing communication between said space and the inlet 240 of the circulating pump 235.

The pump 235 also has an outlet 245 which is connected by a hose section 246 to a pipe nipple 247, which in turn is mounted on one side of a T-fitting 248. The opposite side of the T-fitting is connected to a heat exchange coil 249 which is preferably spirally wound and takes the general shape of a pancake. This construction reduces the space occupied by the coil 249 to a minimum and thus enables the construction to be more compact. The opposite end of the coil 249 is connected to one side of a T-fitting 250 and a pipe nipple 251 is threaded into the opposite side of said T-fitting. A section of hose 252 connects the pipe nipple 251 with a pipe elbow 253 connected with the stem opening of a T-fitting 254. A pipe nipple 255 is mounted in one side of the T-fitting 254 and one end of a hose 256 is secured to the pipe nipple 255 and its opposite end is adapted to be inserted through the neck of the radiator R into the space R' so as to serve as a return for the cooled liquid from the heat exchange coil 249.

The heat exchange coil 249 is mounted upon the platform 231 by a pair of brackets 257 welded to said coil and bolted at 257^a to said platform. Said coil contains a plurality of small copper tubes 258 (Figs. 7 to 9). The opposite ends of these tubes are mounted in plugs 259 which are sealed at their periphery in the pipe nipples 247 and 251 so that the cooling medium withdrawn from the radiator R through the hose section 244 by the pump 235 and returned through the hose section 256 can pass through the coil 249 only by way of the tubes 258, the direction of circulation being as indicated by the arrows in Fig. 7.

A length of hose 260 has one end thereof provided with a female coupling element 261 adapted to be connected to the male coupling element 204 of a water supply line (Fig. 1) and the opposite end of said hose is connected by a pipe nipple 262, T 263 and pipe nipple 264 to the stem of the T 250. As will be noted from Fig. 7, cooling water from the hose 260 is discharged into the T-fitting 250 so that it passes along the outside of the tubes 258 to cool the radiator liquid in said tubes, the direction of flow of the cooling water being opposite to that of the liquid circulating in said tubes. The cooling water after passing through the heat exchange coil 249 discharges into the T-fitting 248 and enters a pipe 265, the upper end of which is mounted in the stem of said T and the lower end of which carries a three-way elbow 266. One leg of the elbow has a pipe nipple 267 mounted therein, the opposite end of said pipe nipple being connected to a valve 268 operable by a handle 269 carried by a stem 270 which projects through the front panel 215 of the cabinet 212

(see Fig. 4). The valve 268 is of the angle type and is connected to one leg of a by-pass 271 (Fig. 7), the opposite leg of which by-pass is connected to the second leg of the three-way elbow 266. The by-pass piping 271 includes a T 272 to which is connected one end of a length of hose 273. The opposite end of the length of hose 273 carries a male coupling element 274 adapted to be connected to a female coupling element 205 (Fig. 1) associated with a suitable drain.

The valve 268 may be manually adjusted to control the rate at which cooling water passes through the heat exchange coil 249. However, the by-pass piping 271 is provided with a solenoid valve 275 controlled by a thermostat T, which is adapted to be positioned upon any suitable portion of the engine block. This thermostat is fully disclosed in my Patent 2,417,860, supra, and includes a permanent magnet (not shown herein), which enables the same to adhere to any desired portion of the engine, either the head or the block. The thermostat T automatically controls the solenoid valve 275 to open the same to permit the cooling water to discharge at a faster rate than the given adjustment of the manually operated valve 268 will permit. Any water flowing through the by-pass piping 271, of course, will be conducted to waste from the instrument stand through the hose 273.

In the event that the radiator R is not completely filled at the beginning of the test, the same can be filled with the present apparatus by simply pressing a plunger 276 slidably mounted in the side wall 213 of the cabinet 212. The plunger 276 is arranged to effect opening of a valve 277 so as to by-pass water from the T-fitting 263 through a section of hose 278, a conduit 278^a and T 254 into the hose 256 from whence it is discharged into the tank R'. Thus, filling of the radiator is made a very simple operation with the present construction which conveniently enables the radiator R to be filled without the use of a can or bucket, etc.

The total volumetric capacity of the three small tubes 258 is such that it is less than the volume of the tank space R' in the smallest radiator of the average automobile. This makes it possible to cool the medium in the radiator R without draining said radiator and without withdrawing so much liquid from the radiator as might produce undesirable engine heating. In actual operation, the heat exchange coil 249 is empty at the beginning of the test. The circulating pump 235 is started and a suction is created in the hose section 244 inducing the radiator liquid to enter. The hose 244 conducts said liquid to the pump inlet 240 so that the pump will immediately begin to withdraw the liquid from the space R' and introduce it into the small tubes 258 of the heat exchanger through the hose 246. Cooled radiator liquid is delivered to the space R' from the return hose 256. After the test has been completed, it is only necessary to remove the hose 244 from the space R' and permit the pump to draw air and force said air into the tubes 258 to discharge all of the liquid therefrom and cause the same to be returned to the space R' through the return hose 256. In this manner, none of the original radiator liquid is lost.

The instrument stand S is constructed so that it affords the added advantage of permitting the dynamometer to be used for comparative tests of the power values of different types or grades of motor fuel. The construction is such that a change-over can be quickly made from one type

of fuel to another and the difference in speed and horsepower developed by the respective fuels noted from the gauges on the instrument stand. As will be noted from Figs. 4 and 5, the cabinet 212 contains two tanks 285 and 286. These tanks are supported by strips of angle iron 287 extending across the cabinet and secured at their opposite ends to transverse angle strips 288, one of which is bolted at 289 to the vertical partition 213^a and the other of which is screwed at 290^a to the end wall 214. The tanks 285 and 286 are held upon the strips 287 by metal straps 290.

Each of the tanks is provided with a filling neck 291 adapted to receive a cap 292 and is further provided with a fuel gauge 293 to indicate the amount of fuel contained in said tanks. The tank 286 has an outlet pipe 294 which is connected to a conventional three-way valve 295. The stem 296 of said valve projects through the front panel 215 of the cabinet 212 and carries a handle 297 through which the valve can be actuated from the exterior of the cabinet. The tank 285 has an outlet pipe 298 which is also connected to the three-way valve 295. The three-way valve 295 is also connected to the inlet side of an electrically operated (electromagnetic) fuel pump 299 by a conduit 300. The outlet side of the fuel pump 299 is connected to a conduit 301 which extends upwardly to a point adjacent the upper end of the partition 213^a (Fig. 3) where it is connected to a flexible hose or fuel line 302. The opposite end of the fuel line 302 is provided with a fitting 303, whereby the same can be connected to the carburetor or fuel line (not shown) on the car being tested. It will be understood that when the handle 297 is in the vertical position, the flow of fuel from both tanks 285 and 286 to the fuel pump is cut off by the three-way valve 295, and that when the handle is turned from the vertical clockwise, as viewed in Fig. 3, to a substantially horizontal position, fuel will be withdrawn from the tank 286, and when said handle is turned counterclockwise from said vertical position, fuel will be withdrawn from the tank 285.

The valve stem 296 carries an eccentric 304 adapted to actuate a switch mechanism 305 to start the motor of the fuel pump 299 simultaneously with the opening of the three-way valve 295 by turning the handle 297 in either direction. In this connection the instrument panel carries suitable translucent glass or plastic elements marked, for example, "Premium" and "Regular," respectively, which may be automatically illuminated, if desired, in accordance with the direction in which the handle 297 is turned. This lighting can be conveniently controlled by the switch mechanism 305, as will be readily understood.

The intermediate partition wall 213^a is formed integral with parallel partition walls 306 (Fig. 6) which terminate in flanges 307 secured to the end wall 213 by screws 308. A horizontal wall 309 (Fig. 3) is formed at the lower end of the walls 213^a and 306 and forms a bottom for a well 310 which is adapted to receive the radiator hose lines 244 and 256, the fuel line 302 and a cable 311 connected with the thermostat T. The well 310 contains a cylindrical weight 312 which overlies the hose lines 244 and 256, fuel line 302 and cable 311 which form loops in the well 310 in the manner indicated in Fig. 3. The object of the weight 312 is to automatically maintain the hose lines and cable retracted into the well and out of the way when not in use. The hose lines 244 and 256 are preferably provided with suitable fittings 313 and

314 which prevent the ends thereof from dropping back into the well 310 when the hose is retracted.

Instead of using a single well 310 and weight 312, separate wells and individual weights may obviously be provided for the hose lines 244, 256, 302 and the cable 311, if desired.

Insofar as the thermostat T is concerned, it will be sufficient for present purposes to point out that the same includes a thermally responsive element 335 (Fig. 7) in the form of a Bourdon tube, one end portion of which is substantially flat and the opposite end of which carries a contact element 338. The tube 335 is filled with acetone or some other suitable liquid which will expand and contract in accordance with temperature changes. The contact 338 is adapted to engage a contact 339. The wiring for connecting the thermostat T with the remainder of the apparatus is conveniently contained in the cable 311.

It will be understood from the well known principle of operation of the Bourdon tube that when the liquid in the tube 335 expands, the curved portion of the tube will tend to straighten out and in doing so will cause the contact 338 to engage the contact 339 and thereby complete a circuit to the solenoid valve 275 controlling the rate of flow of cooling water through the heat exchanger 249 for cooling the radiator water, as will be explained later.

The thermostat T may be positioned upon any ferrous part of the engine and will automatically adhere thereto because of the attraction of its permanent magnet (not shown). It is preferable to place the thermostat T on either the head or some part of the engine block, fairly remote from the exhaust manifold so that it will not be influenced by high radiation temperatures.

The circuit for controlling the operation of the circulation pump 235 and the solenoid valve 275 is schematically shown in Fig. 7. Alternating current is supplied to the apparatus (instrument stand) through main lead lines a and b. A toggle switch c is connected in the line a and controls the supply of current to a toggle switch d, which in turn controls the supply of current to the motor 230 and to a relay 345 which controls the solenoid valve 275. The switches c and d are connected in series and mounted upon a switch panel e, the former switch being marked "Main" and the latter "Cooler." The switch panel e is conveniently mounted upon an instrument panel e' within the instrument stand S. The switch d is directly connected by a line f with one side of the motor 230, and a line g connects the other side of said motor 55 with the main lead b. Accordingly, the motor 230 will start the radiator water circulating pump 235 whenever the switch d is actuated to its "on" position (assuming the main switch c is closed).

One side of a primary coil of a transformer h is connected with the line f and the opposite side of said primary coil is connected with the line g. The secondary coil of the transformer h is connected across a copper oxide rectifier i for supplying direct current to actuate the coil of the relay 345, inasmuch as such current is preferred to A. C. in relay operation. A line j connects the rectifier i with the contact 339 of the thermostat T and a line k connects said rectifier with a contact m of the relay coil 345^a. The other contact n of the relay coil 345^a is connected by a line o with the other contact 338 of the thermostat T. Current for actuating the solenoid valve 275 is supplied to the relay 345 by a line p connected at one end with the switch d and at its opposite end to a contact p' on said relay. A contact p² on said

relay is also connected to the line *p* by a line *p*². The circuit from the relay 345 to the solenoid valve 275 is completed by a line *q* connected to relay contact *q'* at one end and with one side of the solenoid valve 275 at its opposite end. A line *r* connects the other side of the solenoid valve 275 with the line *g* going to the main lead *b*. The relay 345 also has a contact *s* which is connected by a line *t* to one side of the signal lamp *u*. The opposite side of this signal lamp is connected by a line *v* with the line *g*. The relay 345, transformer *h* and rectifier *i* are all mounted upon the instrument panel *e'*, as indicated in Fig. 4.

Assuming that the "Main" switch *c* and the "Cooler" switch *d* have been closed, current will be supplied to the motor 230 through the lines *f* and *g*. This starts the circulating pump 235 of the auxiliary radiator liquid cooling system. Simultaneously, current is supplied to the transformer *h* and rectified to D. C. in the rectifier *i* so that D. C. will be available to actuate the relay coil 345^a when the contacts 338 and 339 of the thermostat *T* are engaged. When the circuit to the relay coil 345^a is completed, current will be supplied to the solenoid valve 275 through the lines *p* and *q*, and the circuit from the solenoid valve will be completed through the lines *r* and *g*. Energization of the solenoid valve 275 opens said valve to permit an increased volume of cooling water to pass through the heat exchanger, as previously explained. Simultaneously, with the completion of the circuit to the solenoid valve 275, the circuit to the signal lamp *u* will be completed through the lines *t* and *v* so that the signal lamp will be lighted to indicate that said valve is open.

The thermostat *T*, in addition to controlling the temperature of the engine undergoing test, also serves as a safety means in the event that the operator neglects to turn the handle 269 to open the hand valve 268. As will be apparent from Fig. 7, cooling water can be discharged from the heat exchanger 249 through the bypass 271 and conduit 273 when the solenoid valve 275 is opened, even though the valve 268 should be left unopened.

The thermostat *T* is calibrated so that when the liquid in the engine being tested reaches a temperature of about 175° F., the Bourdon tube 335 expands and the thermostat contacts 338 and 339 are engaged to operate the relay coil 345^a, as described hereinabove. When the solenoid valve 275 is opened, the cooling water is allowed to flow from the heat exchanger 249 at a greater rate than is permitted by the manually operated valve 268 alone. In this manner, the water or other medium flowing through the tubes 258 is cooled to a relatively lower temperature during its flow through the heat exchanger 249, which soon reduces the temperature of the engine. The thermostat *T* is further calibrated so that when the temperature of the engine liquid has dropped to about 165° F., the contacts 338 and 339 automatically separate due to contractive movement of the tube 335, and the current to the relay coil 345^a is thus cut off. The valve 275 then closes, as previously described, causing a reduction in the amount of cooling water flowing through the heat exchanger 249. Thus, by proper and automatic control of the opening and closing of the solenoid valve 275, the temperature of the engine undergoing test can be made to closely approximate that encountered in road driving.

It will be understood that the invention is not

75

limited to use with the particular thermostat means disclosed herein and that, if desired, a conventional immersion type thermostat may be mounted in the engine head or block for controlling the solenoid valve 275, although it will be apparent that the present thermostat avoids the labor and waste of time incident to installing and immersion type of thermostat, and, moreover, there is no loss of liquid from the engine as when an immersion thermostat is installed. As a further possible means of control, a conventional thermostat may be associated with the radiator in the usual manner, although such type of thermostat is apt to be less accurate inasmuch as the temperature of the radiator liquid may vary considerably from the temperature of the liquid in the water jacket of the engine.

The thermostat *T*, when not in use is adapted to be positioned out of the way upon a plate 315 (Fig. 5) carried by the instrument stand, the thermostat cable 311 being retracted into the well 310, as aforescribed.

The instrument stand *S* carries a direct reading speed meter 350 graduated to indicate miles per hour and a direct reading power meter 351 graduated to indicate horsepower. The operation of these meters is very simple and quite accurate, and the circuit and operating devices therefor are described in detail, and claimed, in my copending application Serial No. 775 765 filed of even date herewith, and which is a continuation-in-part of my parent application, Serial No. 443,833, *supra*.

The instrument stand *S* also carries a bracket 228 on the wall 213 thereof provided with fingers 229 (Figs. 1 and 5) adapted to support a remote control device 167 for controlling the loading and unloading of the hydraulic brake unit (not shown) through the actuation of an "On" switch 168 and an "Off" switch 171, all as fully disclosed, and claimed, in my parent application Serial No. 443,833, *supra*.

An illustration of one use of the present invention, the vehicle to be tested is driven or backed onto the dynamometer rolls 10 and 11 so that the rear wheels *W* rest between said rolls. A chock *Y* is placed in front of each front wheel as a safety precaution to prevent the vehicle from moving forward, as shown in Fig. 2, although this is not necessary because the wheels *W* will remain between the rolls 10 and 11 regardless of the speed at which they are driven. The stand *S* is conveniently positioned near the engine radiator, so that its instruments can be viewed by the operator.

At the beginning of the test of a vehicle, the radiator cap (not shown) of the radiator *R* is removed and the inlet hose 244 and the return hose 256 are inserted into the tank space *R'* through the neck of the radiator. If the radiator tank requires filling, water can be added by depressing the plunger 276 of the valve 277 to by-pass some water into the radiator, as previously described. The thermostat *T* is then positioned upon the desired portion of the engine. The "Main" switch *c* and "Cooler" switch *d* are then thrown to their "On" position. Actuation of the "Cooler" switch *d* will start the circulating pump 235 by completing a circuit to the pump driving motor 230, as aforescribed. The pump 235 is a positive displacement pump and, therefore, when it starts, it will ordinarily prime itself from the water or other liquid available in the radiator *R*.

After the auxiliary cooling system for the ra-

diator liquid has been started, the handle 269 is operated to adjust the valve 268 to allow cooling water to pass through the heat exchanger 249. The vehicle engine is then started in the conventional manner and is subjected to such tests of speed, load or acceleration as may be desired, the auxiliary cooling system functioning to cool the engine to a temperature comparable to that encountered under road driving conditions. After the tests have been completed, the inlet hose 244 is withdrawn from the radiator tank R' so that withdrawal of liquid from the engine cooling system ceases. However, the motor-driven pump 235 is permitted to run for an interval of time sufficient to pump all of the liquid out of the heat exchanger 249 back into the radiator R through the return hose 256. Thus, none of the radiator liquid is lost or wasted and satisfactory cooling of the engine is effected with a minimum of inconvenience to the user of the apparatus. The vehicle can be readily driven off the rolls 10 and 11 by locking either, for example, by a pawl and ratchet, as disclosed in my copending application Serial No. 775,768, supra.

It will be understood that various changes may be made in the details of construction and arrangement of the parts shown herein without departing from the spirit of the invention or the scope of the appended claims.

I claim:

1. A method of cooling an engine of a motor vehicle undergoing test, comprising the steps of: withdrawing liquid from the vehicle radiator at a given rate, cooling said withdrawn liquid, and returning said cooled liquid to said radiator at the same rate at which it is withdrawn.

2. The method of cooling an engine of a motor vehicle while undergoing test, comprising the steps of: continuously withdrawing engine cooling liquid from the vehicle radiator at a given rate; cooling the withdrawn liquid; and returning the withdrawn, cooled liquid to said radiator at the same rate at which it is being withdrawn.

3. The method of cooling an engine provided with a cooling system, while undergoing test, comprising the steps of: supplementing the cooling effect of said cooling system by continuously pumping liquid out of the engine cooling system at a given rate; cooling the withdrawn liquid; and returning the withdrawn, cooled liquid to said cooling system at the same rate at which it is being withdrawn.

4. The method of cooling an engine of a motor vehicle provided with a cooling system normally capable of satisfactorily cooling said engine while on the highway, but incapable per se of satisfactorily cooling said engine while undergoing tests on a chassis dynamometer, comprising the steps of: supplementing the cooling action of said engine cooling system by continuously removing a portion of the engine cooling liquid from the engine cooling system; cooling the removed liquid; and then returning the removed, cooled liquid to said cooling system.

5. The method of cooling an engine of a motor vehicle provided with a cooling system normally capable of satisfactorily cooling said engine while moving on the highway but incapable per se of satisfactorily cooling said engine while undergoing tests on a chassis dynamometer, comprising the steps of: continuously pumping a portion of the engine cooling liquid out of the engine cooling system; cooling the withdrawn liquid; and continuously pumping the withdrawn, cooled liquid back into said cooling system at the same

rate at which it is being pumped out of said system.

6. Auxiliary cooling means for use with a radiator for cooling the liquid of a motor vehicle engine while undergoing test, comprising: a heat exchanger for cooling the cooling liquid of an engine undergoing test; conduit means for connecting the radiator of said motor vehicle with said heat exchanger arranged to provide an uninterrupted circulating system exteriorly of said radiator and engine through which said engine cooling liquid is circulated, cooled and returned to said radiator; and means for continuously withdrawing said engine cooling liquid from said radiator and circulating said liquid through said system.

7. Auxiliary cooling means for use with a radiator for cooling the liquid of a motor vehicle engine while undergoing test, said radiator having a tank portion at its upper end, comprising: a heat exchanger for cooling the cooling liquid of an engine undergoing test; a pump having an inlet and an outlet; means connecting the outlet of said pump with the inlet of said heat exchanger; a flexible conduit connected at one end with the inlet of said pump and adapted to have its other end inserted in the tank portion at the upper end of said radiator; and a second flexible conduit having one end connected with the outlet of said heat exchanger and adapted to have its other end inserted into said tank portion.

8. Auxiliary cooling means for use with a radiator for cooling the liquid of a motor vehicle engine while undergoing test, comprising: a heat exchanger for cooling the cooling liquid of an engine undergoing test; means including a pump and conduits arranged to provide an uninterrupted circulating system for the engine cooling liquid exteriorly of the radiator and engine, and arranged so that the pump withdraws liquid from the radiator, causes said liquid to be circulated through said heat exchanger to be cooled and then returned to said radiator; means for effecting cooling of the engine cooling liquid while it is circulating through said heat exchanger including an electromagnetic valve for controlling the rate of flow of cooling water through said heat exchanger; and means responsive to temperature changes in the engine for controlling the operation of said electromagnetic valve.

9. Cooling means for use with chassis dynamometer apparatus for testing an engine having a radiator associated therewith, comprising: a heat exchanger for cooling the radiator liquid of an engine while undergoing test, said heat exchanger having a small volumetric capacity compared with that of the radiator, whereby only a relatively small part of the engine cooling liquid can be withdrawn from the radiator at any given time; conduit means for conducting the engine cooling liquid to and from said heat exchanger arranged to provide a closed system through which said engine cooling liquid is circulated, cooled and returned to said radiator; and a pump connected in said conduit means for effecting withdrawal of the engine cooling liquid from said radiator and circulation thereof through said heat exchanger and return to said radiator.

10. Cooling means for use with apparatus for testing an engine, comprising: a heat exchanger for cooling the cooling liquid of an engine undergoing test, said heat exchanger having a small volumetric capacity compared with that of the engine cooling system, whereby only a relatively small part of the engine cooling liquid can be

withdrawn from said system at any given time; conduit means for conducting the engine cooling liquid to and from said heat exchanger arranged to provide a closed system through which said engine cooling liquid is circulated, cooled and returned to said system; and a pump connected in said conduit means for effecting withdrawal of the engine cooling liquid from said system and circulation thereof through said heat exchanger and return to said system.

11. Apparatus for use with a chassis dynamometer, comprising: a stand containing a cooling system including a heat exchanger and a pair of hose sections, one end of each of said hose sections being in communication with said heat exchanger and the opposite end of said hose sections being adapted to be inserted into the upper tank portion of the radiator of a vehicle undergoing test; and a pump in said stand operatively connected with said heat exchanger and hose sections for withdrawing the liquid from the radiator through one of said hose sections and pumping said liquid into and through said heat exchanger and returning said liquid through the other of said hose sections to said radiator.

12. Apparatus for use with a chassis dynamometer, comprising: a stand containing a cooling system including a heat exchanger and a pair of hose sections, one end of each of said hose sections being in communication with said heat exchanger and the opposite end of said hose sections being adapted to be inserted into the upper tank portion of the radiator of a vehicle undergoing test; a pump in said stand operatively connected with said heat exchanger and hose sections for withdrawing the liquid from the radiator through one of said hose sections and pumping said liquid into said heat exchanger and returning said liquid through the other of said hose sections to said radiator; a well in said stand into which said hose sections are adapted to be retracted when not in use; and means for automatically retracting said hose sections into said well.

13. Apparatus for use with an engine dynamometer, comprising: a stand containing an auxiliary cooling system including a heat exchanger and a pair of hose sections, one end of each of said hose sections being in communication with said heat exchanger and the opposite end of said hose sections being adapted to be inserted into the upper tank portion of a radiator; a pump in said stand operatively connected with said heat exchanger and hose sections for withdrawing the liquid from the radiator through one of said hose sections and pumping said liquid into said heat exchanger and returning said liquid through the other of said hose sections to said radiator; a well in said stand into which said hose sections are adapted to be retracted; and weight means for automatically retracting said hose sections into said well.

14. Auxiliary cooling means adapted to be used with a radiator for cooling the liquid of a motor vehicle engine undergoing test, comprising: a heat exchanger containing a plurality of tubes of relatively small diameter through which the engine cooling liquid is adapted to be circulated, said heat exchanger having an inlet and an outlet for said engine cooling liquid; means including an inlet conduit connected with the inlet of said heat exchanger for conducting the engine cooling liquid from said radiator to said tubes; return conduit means for connecting the outlet of said heat exchanger with said ra-

diator for returning the cooled engine liquid to said radiator, whereby to provide a closed circulation system for said engine liquid; a supply pipe connected with said heat exchanger for introducing cooling water thereto for contact with the exterior surface of said tubes; a discharge pipe for draining the cooling water from said heat exchanger; and a conduit having a valve connected therein arranged to by-pass

5 water from said supply pipe to said return conduit, whereby the water level in said radiator can be raised at the beginning of the test, if necessary.

15. Auxiliary cooling means adapted to be used with a radiator for cooling the liquid of a motor vehicle engine while undergoing test, comprising: a heat exchanger, said heat exchanger having an inlet and an outlet for said engine cooling liquid; supply piping connected with one end of said heat exchanger for introducing cooling water thereto; discharge piping connected with the opposite end of said heat exchanger for discharging the cooling water from said heat exchanger, said discharge piping including a manually operable valve for controlling the rate at which cooling water can flow through said heat exchanger, said discharge piping also including a by-pass having a solenoid valve arranged to be opened when the engine cooling liquid reaches 20 a predetermined temperature, to thereby increase the volume of cooling water discharging from said heat exchanger; thermally responsive means connected with said solenoid valve for controlling said solenoid valve in accordance with changes in the engine cooling liquid temperature; a pump for circulating the engine cooling liquid through said heat exchanger, said pump having an inlet and an outlet; conduit means connected with said pump inlet having an end 25 adapted to be inserted into the upper tank portion of a radiator for conducting the engine cooling liquid from the radiator to the pump inlet; conduit means connecting the outlet of said pump to one end of said heat exchanger for introducing the engine cooling liquid into said heat exchanger; and conduit means connected with the opposite end of said heat exchanger for returning the engine cooling liquid to said radiator.

16. Auxiliary cooling means adapted to be used with a radiator for cooling the liquid of a motor vehicle engine undergoing test, comprising: a heat exchanger containing a plurality of tubes of small diameter for the engine liquid to be cooled, said heat exchanger having an inlet and an outlet for said engine liquid; piping connected with one end of said heat exchanger for introducing cooling water for contact with the exterior surface of said tubes; discharge piping connected with the opposite end of said heat exchanger for discharging the cooling water from said heat exchanger, said discharge piping including a manually operable valve for controlling the rate at which cooling water can flow through said heat exchanger, said discharge piping also including a by-pass having a solenoid valve arranged to be opened when the engine cooling liquid reaches a predetermined temperature, to thereby increase the volume of cooling water discharging from said heat exchanger; thermally responsive means connected with said solenoid valve for controlling said solenoid valve in accordance with changes in the engine cooling liquid temperature; a pump for circulating the engine cooling liquid through said tubes, said pump having an inlet and an outlet; conduit

15

means connected with said pump inlet having an end adapted to be inserted into the upper tank portion of a radiator for conducting the engine cooling liquid from the radiator to the pump inlet; conduit means connecting the outlet of said pump to one end of said heat exchanger for introducing the engine cooling liquid into said tubes; and conduit means connected with the opposite end of said heat exchanger for returning the engine cooling liquid to said radiator.

17. Auxiliary cooling means adapted to be used with a radiator for cooling the liquid of a motor vehicle engine undergoing test, comprising: a heat exchanger including a spirally wound pipe coil of generally pancake shape; a plurality of tubes of small diameter disposed in said pipe coil; piping connected with one end of said pipe coil for introducing cooling water into said pipe coil for contact with the exterior surface of said tubes; discharge piping connected with the opposite end of said pipe coil for discharging the cooling water from said pipe coil, said discharge piping including a manually operable valve for controlling the rate at which cooling water can flow through said pipe coil, said discharge piping also including a by-pass having a solenoid valve arranged to be opened when the engine cooling liquid reaches a predetermined temperature, to thereby increase the volume of cooling water discharging from said pipe coil; thermally responsive means connected with said solenoid valve for controlling said solenoid valve in accordance with changes in the engine cooling liquid temperature; a pump for circulating the engine cooling liquid through said tubes, said pump having an inlet and an outlet; conduit means connected with said pump inlet having an end adapted to be inserted into the upper tank portion of a radiator for conducting the engine cooling liquid from the radiator to the pump inlet; conduit means connecting the outlet of said pump to one end of said pipe coil for introducing the radiator liquid into said tubes; and conduit means connected with the opposite end of said pipe coil for returning the engine cooling liquid to said radiator.

18. Auxiliary cooling means adapted to be used with a radiator for cooling the liquid of a motor vehicle engine undergoing test, comprising: a heat exchanger including a spirally wound pipe coil of generally pancake shape; a plurality of tubes of small diameter disposed in said pipe coil; inlet piping connected with one end of said pipe coil for introducing cooling water into said pipe coil for contact with the exterior surface of said tubes; discharge piping connected with the opposite end of said pipe coil for discharging the cooling water from said pipe coil, said discharge piping including a manually operable valve for controlling the rate at which cooling water can flow through said pipe coil, said

60

16

discharge piping also including a by-pass having a solenoid valve arranged to be opened when the engine cooling liquid reaches a predetermined temperature, to thereby increase the volume of cooling water discharging from said pipe coil; thermally responsive means connected with said solenoid valve for controlling said solenoid valve in accordance with changes in the engine cooling liquid temperature; a pump for circulating the engine cooling liquid through said tubes, said pump having an inlet and an outlet; conduit means connected with said pump inlet having an end adapted to be inserted into the upper portion of a radiator for conducting the engine cooling liquid from the radiator to the pump inlet; conduit means connecting the outlet of said pump to one end of said pipe coil for introducing the engine cooling liquid into said tubes; return conduit means connected with the opposite end of said pipe coil for returning the engine cooling liquid to said radiator; and a conduit having a by-pass valve between said return conduit means and said inlet piping for by-passing cooling water to said return conduit means to fill the radiator at the beginning of the test, if necessary.

19. Auxiliary cooling means for use with a radiator for cooling the liquid of a motor vehicle engine while undergoing test, comprising: a heat exchanger through which the engine cooling liquid is to be circulated, said heat exchanger having an inlet and an outlet for said engine cooling liquid; means including an inlet conduit connected with the inlet of said heat exchanger for conducting the engine cooling liquid from said radiator to the inlet of said heat exchanger; return conduit means for connecting the outlet of said heat exchanger with said radiator for returning the cooled engine liquid to said radiator, whereby to provide a closed circulation system for said engine cooling liquid; a supply pipe connected with said heat exchanger for introducing cooling water thereinto; a discharge pipe for draining the cooling water from said heat exchanger; and means for diverting water from said supply pipe to said return conduit, whereby the water level in the radiator can be raised at the beginning of the test, if necessary.
